WOLF-SHAPED SEAT FOR PLAYGROUND APPARATUS

Robert S. Wormser, Hillsdale, Mich., assignor to Game Time, Inc., Litchfield, Mich., a corporation of Michigan

Filed Dec. 30, 1968, Ser. No. 15,141

Term of patent 14 years

Int. Cl. D21—04

U.S. Cl. D34—15

FIG. 1

FIG. 3

FIG. 1 is a side, elevational view of a wolf-shaped seat for a playground apparatus in accord with my new design, the opposite side thereof being identical thereto, FIG. 2 is a top plan view,

FIG. 3 is a front, elevational view of my new design, and

FIG. 4 is a rear, elevational view.

I claim:

The ornamental design for a wolf-shaped seat for playground apparatus, substantially as shown and described,
